STOP FOR SLIDING DOORS

Ralph W. Reynolds, Indianapolis, Ind., assignor
to Holcomb & Hoke Mfg. Co., Inc., Indianapolis,
Ind., a corporation

Application April 30, 1952, Serial No. 285,343

6 Claims. (Cl. 160—195)

1

This invention relates to an automatic stop device for sliding doors having a pivoted switch mounting for transferring the sliding doors from one track to another angularly disposed track, and may be applicable to solid sliding doors, but more particularly to fabric folding doors of the character disclosed in the application for Letters Patent of Frank J. Hoke and Ralph W. Reynolds filed November 27, 1950, Serial No. 197,776, entitled "Folding Door Construction."

In folding doors of the above character it is often desirable to switch them from one track to another track, for example, from a main track where the door serves the purpose of a closure for an opening in one wall of a room, to a storage track aligned near the adjacent wall of the room. In this manner, and particularly wherein the door closure may be in several sections to close a wide opening, and in folding a door or doors to open position, they may interfere with the extent of the desired opening. In such cases the door or doors sliding on the main track for closing the main opening in the room may be slid onto a swinging track and swung a quarter circle against a side wall so as to be completely out of the way of the main opening in the room, or transferred from the swinging track onto an auxiliary storage track extending along such wall. Again, the room may have openings in adjacent walls, using the same door or doors for closing one or the other opening by switching the door therebetween on the swinging track.

However, it is desirable to provide an automatic stop for preventing the sliding door from running off of the main or auxiliary track when the switch track is out of alignment therewith, and which will automatically open up the ends of the main or auxiliary tracks adjacent the switching track when the switching track is moved into alignment therewith for permitting the door or doors to slide therebetween.

This invention therefore relates to an automatic stop for the purposes above described mounted upon an overhead curved track which supports the swinging end of the pivoted switching track, one such stop being positioned at the adjacent end of the main track and another positioned at the end of the auxiliary track. Each of said stops is swung into and out of effective stopping position by a camming action between the stop and one of the supporting rollers on the swinging end of the switching track, as hereinafter more fully set forth and described.

The full nature of the invention will be understood from the following description and claims and the accompanying drawings:

2

Fig. 1 is a sectional diagrammatical illustration of a room showing one wall thereof with an opening adapted to be closed by a sliding door and a closed wall adjacent which the auxiliary or storage track extends, with the switching track intermediate thereof.

Fig. 2 is a plan view of the switching track mounting swung into alignment with the main track for receiving or discharging a sliding door.

10 Fig. 3 is an illustrative view of the automatic stop viewed on the line 3—3 of Fig. 2, showing it in ineffective open position, the switching track being removed.

15 Fig. 4 is the same as Fig. 3, showing the stop in effective stopping position.

In the drawings there is shown a sectional portion of a room or compartment having a closed side wall 10 and an open front wall 11. The front wall 11 is provided with a sliding and folding door of the fabric type indicated at 12 in its extended closing position and at 13 in its folded opening position. Said door slides upon a fixed main track indicated at 14 extending across the underside of the usual sill defining the top of the opening 11. A corresponding overhead fixed auxiliary storage track 15 may be disposed along the wall 10 for receiving one or more doors 13a in its folded position. At the juncture of the walls 10 and 11 there is mounted an overhead swinging switch track 16 for switching the folded door 13 to the position of the folded door 13a. The switch track being overhead, it is out of the way of the wall opening 11 so that in place of the folded door 13 being moved on its main track 14 against the wall 10 and thereby taking up substantial space, by sliding it onto the switch track and swinging it against the wall 10, the entire opening will be free of the folded door.

As shown in Fig. 1 the wall opening 11 is of 40 a length running from one side wall to another, upon which there may be two or more folding doors 12, 13, in which event the auxiliary storage track 15 is provided for receiving them one at a time as they are switched thereto by the switch track 16. However, if the width of the wall opening 11 is no greater than that of one door, there would be no need for providing the storage track, the switch track being sufficient to swing the single door out of the way. Various arrangements of the character above described may be provided, including a switch track at the other corner of the room, where desirable, or the wall 10 may have an opening similar to the opening 11 and doors switched from one opening to the other.

The switch track 16 is shown in Fig. 2 as being

in cross section identical with the main track 14 and the auxiliary storage track 15. Said tracks are shown in section in Figs. 3 and 4, and are each provided with the runways 17 upon which the door sliding members or rollers 18 are adapted to ride. Said rollers are mounted upon a door supporting carriage 19 from which depend pivot pins 20 which carry the lazytong supports 21 of the fabric doors 12, 13.

The switch track 16 is pivotally mounted at 22 to an overhead structure of the room (not shown), and is closed at one end by a fixed stop member 23. The free end of the switch track 16 is supported by a bracket 24 which carries a pair of rollers 25 and 26. The rollers 25 and 26 roll upon an arcuate transfer track 27 likewise secured to the overhead structure of the room. Said transfer track extends about a quarter circle with its radius of curvature at the pivotal mounting 22 of the switch track, whereby the switch track may be swung about its pivotal mounting from a position aligning it with the main track 14 and the auxiliary storage track 15, respectively.

When the switch track is swung to its alignment with the main track, the rollers 18 supporting the doors may be rolled from one track to the other. Similarly, when the switch track is swung into alignment with the auxiliary storage track, said rollers may be rolled from one track to the other. Thus a door may be rolled from the main track into the switch track when in alignment therewith, whereupon the switch track may be swung about its pivotal mounting 22 into alignment with the auxiliary storage track, and the door then rolled from the switch track to the storage track. The reverse transfer of the door from the auxiliary storage track back to the main track may be similarly effected through the medium of the switch track.

As above mentioned, wherein the folded door takes up no more space than is permitted by the switch track, the auxiliary storage track may be dispensed with and the door stored upon the switch track when swung over against the wall 10. To permit the rollers 18 carrying the door to pass onto and off of the switch track, the transfer track 27 is notched as indicated at 28 (Figs. 3 and 4), each located opposite the adjacent ends of the main track 14 and the auxiliary storage track 15, respectively. When the door and rollers are carried by the switch track during its swinging movement from one of the tracks 14, 15 to the other, they are prevented from escaping due to the lower portion of the transfer track extending downwardly below the upper portion of the rollers 18. Only when the rollers are brought into registry with the notches 28 are they permitted to pass the transfer track.

When the switch track 16 is moved out of alignment with one or the other track 14, 15, it is desirable to make provision for automatically blocking the ends of said tracks so that a door carried thereby may not roll off of the unprotected end. For that purpose there is provided a pivoted stop member 29 (Figs. 3 and 4) pivotally supported on the convex or outer surface of the transfer track 27 at 30. Said stop member is formed with a stop portion 31 adapted to swing upwardly and downwardly on said track. When in its lower position, as shown in Fig. 4, it extends in the path of the rollers 18 carried by the main track, or, in other words, overlies the notch 28 through which said supports may pass. Thus, when in this position, the stop

member prevents a door from sliding off that end of the main track.

When the stop portion 31 is in its raised position, as shown in Fig. 3, it extends above the rollers 18, opening up the notch 28 so that they may pass from the main track to the switch track, and vice versa. The upper edge of said stop extends above the transfer track in the path of the rollers 25, 26 which roll into and out of the position shown in Fig. 2 relative to the main track, as well as the auxiliary storage track. The stop member 31 is further provided with a hump portion 32 intermediate its ends and a lip portion 33 at the far end thereof.

Referring to Figs. 3 and 4, when the switch track 16 is in alignment with one of the fixed tracks; to receive or discharge a door, the stop member 29 is in its raised position, as shown in Fig. 3, with the roller 26 lying between the lip portion 33 and the hump portion 32, and the roller 25 positioned on the opposite side of the hump portion in the direction of movement of the switch track. With said rollers in this position, the roller 26 holds the lip portion down and the hump portion up, which thereby raises the stop portion 31 free of interference with the movement of the rollers 18. Upon the switch track being swung out of alignment with the fixed tracks, said rollers which carry the switch track will roll in the direction of the arrows. Thus, the roller 26 will roll over the hump portion 32, forcing the stop portion 31 downwardly over the end of the fixed track, where it will remain in its stop position relative thereto so that no door carried thereby can roll off of its open end.

When the switch track is swung back to its aligned position with the fixed track, the roller 26 will roll over the hump portion 32 from the opposite direction into the lip portion 33. Its engagement with the lip portion will force the lip portion downwardly, swinging the stop portion 31 upwardly together with the hump portion 32, freeing the stop from effective stopping position relative to the end of the fixed track. Since the roller 26 will have swung the hump portion upwardly before the roller 25 engages it, said rollers will be thereby arrested in a position straddling the hump portion and with the roller 26 holding the stop portion in its raised position.

It will be observed therefore that the stop member is not only automatically actuated into and out of stopping relation relative to the end of the fixed track, but also serves as a stop to arrest the swinging track in perfect alignment therewith and prevent any overrun thereof. Thus, the stop member serves to both align the swinging and fixed tracks as well as prevent escape of the rollers from the fixed tracks when the switch track is moved out of alignment therewith.

The above description of the stop members similarly applies to the fixed auxiliary storage track 15, there being one such stop member located on the transfer track adjacent the end of each fixed track. In event no fixed auxiliary storage track is necessary or provided, the notch 28 of the transfer track which would otherwise register with the end of said storage track, is blocked off by a suitable plate secured thereover to prevent escape of the rollers 18 from the switch track when it is in storage position.

While the invention has been particularly described with respect to a roller mounted support for a folding door, it may be appreciated that it is equally applicable to the mounting of a solid door, as well as a door having glides or slides

instead of rollers slidably supported upon the several tracks. The doors with respect to which the invention is applicable are, therefore, generally referred to in the appended claims as "sliding doors" whether they are solid, folding, roller-supported or slide-supported, depending upon whether or not the rollers 18 roll upon the tracks or comprise fixed glide members which slide upon the tracks. Similarly, the rollers 25 and 23 may comprise fixed glides which slide upon the transfer track as well as rollers which roll thereon.

The invention claimed is:

1. A switch mounting for sliding doors having a fixed track, a pivotally mounted switch track adapted to swing into and out of door transferring alignment with said fixed track, and a door slidably from one track to the other when aligned, the combination therewith of an arcuate transfer track having its center of curvature in the pivoted mounting of said switch track, a slide member on the free end of said switch track supporting it for swinging movement on said transfer track, and a stop member pivoted on said transfer track adjacent the end of said fixed track and in the path of said slide member, said stop member being engageable by said slide member in one direction for movement to fixed track stop position and in the other direction for movement to fixed track open position.

2. A switch mounting for sliding doors having a fixed track, a pivotally mounted switch track adapted to swing into and out of door transferring alignment with said fixed track, and a door slidably from one track to the other when aligned, the combination therewith of an arcuate transfer track having its center of curvature in the pivoted mounting of said switch track, a slide member on the free end of said switch track supporting it for swinging movement on said transfer track, and a stop and track aligning member pivoted on said transfer track in the path of said slide member for engagement thereby upon said switch track being swung into alignment with said fixed track, said stop having a portion thereof engageable by said slide member for moving it into stop position relative to the end of said fixed track upon said switch track swinging away therefrom and another portion engageable by said slide member for moving it from said stop position and aligning said tracks.

3. A switch mounting for sliding doors having a fixed track, a pivotally mounted switch track adapted to swing into and out of door transferring alignment with said fixed track, and a door slidably from one track to the other when aligned, the combination therewith of an arcuate transfer track having its center of curvature in the pivoted mounting of said switch track, a slide member on the free end of said switch track supporting it for swinging movement on said transfer track, and a stop and track aligning member pivoted on said transfer track in the path of said slide member for engagement thereby upon said switch track being swung into and out of fixed track alignment, said member having a stop portion, a hump portion and a lip portion and movable into stop position relative to the end of the fixed track upon said slide member riding over said hump portion during swinging movement of the switch track from the fixed track, said lip portion being engaged by said slide member upon said switch track being swung to aligned position with said fixed track for raising said stop portion free of said tracks and effecting alignment thereof.

4. A switch mounting for sliding doors having a fixed track and a pivotally mounted switch track adapted to swing into and out of door transferring alignment with said fixed track, and a door having mounting rollers movable over said tracks, the combination therewith of an arcuate transfer track having its center of curvature in the pivotal mounting of said switch track and embracing the free end thereof throughout its swinging movement, said transfer track having a notched opening opposite the end of the fixed track, a pair of spaced switch track rollers carrying the free end of said switch track for supporting it for swinging movement on said transfer track, and a stop member pivoted on said transfer track adjacent the end of said fixed track and in the path of said switch track rollers, said stop member being engageable by at least one of said switch track rollers in one direction for movement to switch track stop position and in the other direction for movement to fixed track open position.

5. A switch mounting for sliding doors having a fixed track and a pivotally mounted switch track adapted to swing into and out of door transferring alignment with said fixed track, and a door having mounting rollers movable over said tracks, the combination therewith of an arcuate transfer track having its center of curvature in the pivotal mounting of said switch track and embracing the free end thereof throughout its swinging movement, said transfer track having a notched opening opposite the end of the fixed track, a pair of spaced switch track rollers carrying the free end of said switch track for supporting it for swinging movement on said transfer track, and a stop and track aligning member pivoted on said transfer track in the path of said switch track supporting rollers for engagement thereby upon said switch track being swung into and out of fixed track alignment, said member having a depending stop portion, an upwardly extending hump portion and an upwardly extending lip portion spaced from said hump portion and related to the swinging movement of said switch track for roller engagement with said lip portion for raising said stop portion out of stop position and positioning between said lip and hump portions for aligning said tracks, said hump portion being engaged by said rollers when moved in the opposite direction for swinging said stop portion downwardly to stop position relative to the end of the fixed track.

6. In a sliding door track structure of the character described, a stop member pivotally mounted adjacent one end of a track having an upwardly extending hump portion, an upwardly extending lip portion spaced therefrom, and a downwardly extending stop portion aligned with said hump portion, and a slide member movable in one direction over said hump portion into engagement with said lip portion for swinging said stop member into hump and stop portion elevated position, and movable in the opposite direction to relieve said lip portion and depress said hump and stop portion.
